Primary Examiner — Kelley A Donnelly(74) Attorney, Agent, or Firm — Stetina Brunda Garred
and Brucker(57) **CLAIM**

The ornamental design for a bar, as shown and described.

DESCRIPTION

FIG. 1 is a front perspective view of the bar of the present invention having a pivoting upper bar surface showing my new design;

FIG. 2 is a rear perspective view thereof;

FIG. 3 is a top plan view thereof;

FIG. 4 is a front elevational view thereof;

FIG. 5 is a bottom plan view thereof;

FIG. 6 is a left side view thereof;

FIG. 7 is a right side view thereof;

FIG. 8 is a rear elevational view thereof;

FIG. 9 is a top plan view illustrating a different orientation

of the upper bar surface of the present invention; and,

FIG. 10 is an upper plan view of the bar of the present invention illustrating the upper bar surface in an additional orientation.

The dotted lines shown in the figures do not form a part of the claimed design.
